CLAIM

The ornamental design for an enclosure for a personal emergency warning device, as shown and described.

DESCRIPTION

FIG. 1 is a perspective view of the top, right and front side of an enclosure for a personal emergency warning device, showing our new design;

FIG. 2 is a front plan view thereof;

FIG. 3 is a back plan view thereof;

FIG. 4 is a right side elevation view thereof;

FIG. 5 is a left side elevation view thereof;

FIG. 6 is a top side view thereof;

FIG. 7 is a bottom side view thereof;

FIG. 8 is a right, front view showing the design in an alternate position thereof; and,

FIG. 9 is a top left rear perspective view thereof.

The broken lines in the drawings represent unclaimed environmental subject matter.
